Attorney.

UNITED STATES PATENT OFFICE.

THEO CLIFFORD WHITING, OF PHILADELPHIA, PENNSYLVANIA.

SPRING-MOTOR.

1,259,570.

Specification of Letters Patent. Patented Mar. 19, 1918.

Application filed August 17, 1916. Serial No. 115,503.

To all whom it may concern:

Be it known that I, THEO CLIFFORD WHITING, a citizen of the United States, residing at Philadelphia, in the State of Pennsylvania, have invented a certain new and useful Improvement in Spring-Motors, whereof the following is a specification, reference being had to the accompanying drawings.

My invention may be employed with particular advantage in the construction of motors for rotating phonograph or gramophone sound record disks. As ordinarily constructed and arranged such motors are not only costly to manufacture but produce an objectionable noise by their operation, which noise is augmented by the acoustic properties of the casings in which such motors are mounted. It is an object of my invention to lessen the cost of manufacture of such motors and render them practically noiseless by a more compact construction and arrangement of their essential elements, in a frame formed of wrought metal elements which are rigidly integrated.

My invention includes the various novel features of construction and arrangement hereinafter more definitely specified.

In said drawings: Figure I is a plan view 30 of a motor conveniently embodying my invention.

Fig. II is an elevation of the right hand side of said motor as indicated in Fig. I.

Fig. III is a front end elevation of said 35 motor.

Fig. IV is a vertical transverse sectional view of said motor, taken on the line IV, IV in Fig. I.

Fig. V is a horizontal sectional view of 40 the upper spring drum of said motor, and its appurtenances.

Fig. VI is an elevation of one end of one of the springs shown in section in the other figures.

Fig. VII is a fragmentary sectional view, 45 showing the construction and arrangement of the adjustable bearing for the worm shaft.

Fig. VIII is a fragmentary sectional view 50 showing the construction and arrangement of the governor mechanism.

Fig. IX is a fragmentary plan sectional view of the winding shaft and its tubular bearing, showing a noiseless clutch in said bearing arranged to permit said shaft to 55 turn in the proper direction but prevent it from turning in the opposite direction.

In said figures; the motor frame includes the two plane sheet metal plates 1 and 2, in parallel spaced relation, the top plate 1 having the flange 3 bent toward the bottom 60 plate 2, at right angles to its plane. Said plates are rigidly connected by the three cylindrical standards 5, each having its upper end rivet headed in engagement with said plate 1 and having at its lower end a 65 screw 6 extending through said plate 2, forming means detachably rigidly connecting it with said plates.

The spring arbor 8 is journaled in said plates 1 and 2, parallel with and between 70 said standards 5, as best shown in Fig. I. The upper spring drum 10 is mounted loose on said arbor and carries, detachably rigidly connected with said drum by the screws 11, the upper drum gear 12 which is also fitted 75 to turn freely on said arbor 8. The spring 14 inclosed by said drum 10 is connected at its outer end to said drum, by engagement of its slot 15 (shown in Fig. VI), with the stud 16 which is riveted in said drum 10 as 80 shown at the right hand side of Figs. IV and V. The inner end of said spring 14 is connected to said arbor 8 by the stud 18 which is, however, detachably fitted in the opening 19 in said arbor. For convenience 85 of illustration, only a few convolutions of the springs are shown in the drawings. However, it is to be understood that said springs actually include many more convolutions, in correspondingly closer relation, 90 and that it is impossible to accidentally displace said stud 18 from its seat in said arbor 8, in which it is detachably fitted to permit the parts to be assembled as hereinafter described.

The lower spring drum 21 is also mounted to turn freely on said arbor 8, and carries, rigidly connected therewith by the screws 22, (similar to the screws 11, but not shown) the lower drum gear 23. Said drum 21 incloses the spring 25, having its outer end connected to the stud 26, which is riveted in said drum, and its inner end connected to the stud 27 which is loosely fitted in the opening 28 in said arbor. 95

The bearing tube 30, shown in Figs. I, II, III and IX is rigidly mounted in said flange 3, in radial relation to said arbor 8. The winding shaft 31 is journaled in said bearing tube 30 and has the gear 32 engaging 100 said upper drum gear 12 as indicated in Figs. II and III. The main shaft 34 is 105

110

journaled, parallel with said spring arbor 8, in said plates 1 and 2 and has its upper portion tapered for detachable engagement with rotary tables for turning sound record disks 5 of any suitable construction. The counter shaft 35 extends parallel with said arbor 8 and main shaft 34, as best shown in Fig. IV, and the worm shaft 37, which carries the worm 38, extends parallel with said winding shaft 31, as best shown in Fig. I. A train of gears which connects said lower drum gear 23 with said counter shaft, main shaft and worm shaft, includes the gear 40 which is rigidly connected with said counter 10 shaft 35, which also has rigidly connected therewith the gear 41 engaging the pinion 42 which is rigidly mounted on said shaft 34. Said shaft 34 also has, rigidly mounted thereon, the worm gear 43 which engages 15 said worm 38, as indicated in Fig. I. Said worm gear 43 and the worm shaft 37 are included in said motor structure merely for the purpose of conveniently actuating the governor mechanism, which is operatively connected with said worm shaft 37. Said governor mechanism includes the friction disk 45 having the hub 46 and axially movable on said shaft 37; means operatively 20 connecting said shaft and disk, tending to 25 axially shift said disk in accordance with the rate of rotation of said shaft, including the sheet metal springs 47 which are detachably connected to said disk hub by the screws 48, and detachably connected, by the 30 screws 50, to the collar 51 which is fixed on said shaft, and weights 52 which are carried by said springs to which they are detachably connected by the screws 49. The 35 construction and arrangement is such that 40 as the rate of rotation of said shaft 37 increases, said friction disk 45 is drawn toward said fixed collar 51, by outward flexure of said springs 47. Such motion is opposed by contact of said disk with the brake block 45 53 (shown in Fig. VIII) which is conveniently formed of oiled leather detachably engaged between opposite flanges 54 on the brake lever 55 which is fulcrumed at its upper corner 56 upon the under face of 50 said frame plate 1. Said brake lever is pressed toward said disk 45 by the spring 58 which is mounted upon the screw 59 which extends through said lever in screw 55 threaded engagement with said plate 1 in which it is jammed by the nut 60. Said lever 55 is prevented from turning horizontally upon said screw 59 by engagement with the opposite side walls of the slot 62 in the flange 3 of said plate 1, through which said 60 lever extends as shown in Fig. III.

In the position shown in Fig. VIII; said lever 55 is held, by said spring 58, in such position as to prevent rotation of said friction disk 45, and consequently stop the motion. However, it is to be understood that

said lever may be depressed to shift said brake block 53 more or less to the right in Fig. VIII, and that the position to which it is thus adjusted will predetermine and limit the maximum rate of rotation of said worm shaft 37, and, consequently, of said main driving shaft 34. That is to say, the maximum limit of rotation of said shaft 34, permitted by said governor mechanism, increases with the increase of movement of 70 said brake block 53 toward the right in Fig. VIII; and increase of the predetermined rate is prevented by frictional engagement of said disk 45 with said brake 53 when that rate is reached, and, as said governor mechanism is so constructed and arranged that it may be used to entirely prevent rotation of said shaft 34, (and thus serve as a stop mechanism), said mechanism may be utilized to predetermine any rate of rotation of said 75 shaft 34, up to the maximum of which the motor is capable. As there is considerable variation in the location of the governor controlling devices which are ordinarily mounted upon the casings in which such 80 motors are inclosed; I find it convenient to provide said lever 55 with means whereby it may be adapted for operation in correspondence with the variations in the location of its actuating means on the casing. Therefore, I provide said lever with the arm 63 conveniently pivotally connected therewith by the rivet 64, so that it may be angularly 85 adjusted, as indicated in Fig. I, to register with any suitable device upon the casing 90 inclosing said motor, whereby said lever 55 may be depressed against the action of said spring 58.

In order that said worm gear 43 may properly engage said worm 38, to actuate 105 the governor mechanism above described; it is necessary to primarily assemble and subsequently maintain them in proper relative position in the motor frame. Therefore, I find it desirable to provide means for precisely adjusting said shaft 37 toward and away from the axis of said worm gear 43, which is the axis of said main driving shaft 34. As shown in Figs. I, IV and VII; the end of said shaft 37 adjacent said worm gear 110 43 is journaled in the socket 66 in the bearing block 67 which is preferably made of hard steel to afford a durable thrust bearing for said shaft 37, which is pressed axially into it by the operation of the motor. Said block 67 is detachably rigidly connected with the stationary frame stud 68 by the screw 69 which extends through the opening 70 in said block, which is sufficiently larger than said screw to permit ample adjustment of 115 said bearing block 67 not only toward and away from said worm gear 43 but longitudinally with respect to said worm shaft 37. Said adjustable bearing block, and its appurtenances are claimed in my copending 120 125 130

application for Letters Patent of the United States which is Serial Number 115,502. Moreover, in order to minimize such vibration of said thrust bearing as would otherwise be permitted by the elasticity and consequent flexure of said frame plate 1; I prefer to stiffen said plate 1 by the reinforcing plate 72 which is rigidly connected therewith by the shank 73 of said stud 68 which extends through said plates 72 and 1, and is rivet headed in engagement with the latter as indicated in Fig. VII. Said plates are also rigidly connected by the rivet 74 at the inner end of said plate 72, as indicated in Figs. I and VII. It may be observed that, as shown in Fig. IV, said reinforcing plate 72 serves as a supplementary bearing for said main shaft 34, in addition to the bearing in said frame plate 1; so that the upper bearing for said shaft 34, which is subjected to the greater portion of the stresses upon said shaft incident to the manipulation of the tables and sound records which it is designed to turn, is reinforced 25 against deforming stresses and wear, by said plate 72.

The proper engagement of said winding gear 32, with the upper drum gear 2 is, of course, dependent upon the assembling and maintenance of said two gears in the proper relation. As shown in Fig. IV, both of the drums 10 and 21, and the gears respectively connected therewith, and which are necessarily loosely mounted on the arbor 8, rest upon each other. Therefore, slight variation in the thickness of the sheet metal from which said drums and gears are pressed would cause variation in the vertical position of said gear 12 unless means were provided to compensate for such variation and insure the presentation of said gear 12 in such vertical position as to properly coöperate with said winding gear 32. I find it convenient to afford such adjustment by providing said arbor 8 with an abutment extending transversely to its axis and with respect to which the elements carried by said arbor 8 are precisely positioned. As shown in Fig. IV, such an abutment is formed by the collar 75 which is driven upon said arbor 8 so as to be rigidly connected therewith. A series of thin sheet metal washers 76 is interposed between said abutment and the adjacent face of the lower drum gear 23, of such number and thickness as to present said gear 12 in the desired position. It may be observed that the vertical adjustment of said gear 23 with respect to the gear 40 upon the counter shaft 35 with which it meshes, does not alter the coöperative relation of said gears. Such means for adjusting the position of said drums upon said arbor 8, necessitates that said drums shall be placed upon and removed from the end of said arbor opposite to said abutment. Conse-

quently, it is necessary that both of the studs 18 and 27, by which the ends of the respective springs 14 and 25 are connected with said arbor, shall be detachably fitted in said arbor, so as to permit the axial movement of 70 said drums 10 and 21 and gears 12 and 23 upon said arbor. Said drums and their appurtenances are assembled upon said arbor as follows: Said studs 18 and 27 being out of said arbor 8; washers 76 of the proper aggregate thickness are placed upon said abutment 75. Said lower drum gear 23 is then placed upon them. The stud 27 is then thrust into the opening 28 in said arbor 8 as shown in Fig. IV. The drum 21, containing the spring 25 in engagement with its stud 26, is then placed upon said arbor and the inner end of said spring snapped into engagement with said stud 27. The upper drum gear 12 is then placed on said arbor, and the stud 18 thrust into the opening 19 in said arbor. The drum 10, containing the spring 14 engaged with its stud 16, is then placed on said arbor and its inner end snapped into engagement with said stud 18; 90 said drums being then rigidly connected with their respective gears, by the screws 11 and 22; the parts are assembled in the co-operative relation shown in Fig. IV.

Although I find it convenient to place the adjusting washers 76 directly upon said abutment 75; it is to be understood that said abutment may be fixed at such a level upon said arbor 8 as to directly support the lower drum gear 23, without the interposition of any adjusting washer, and such washers as are required may be interposed between the upper end of said drum 21 and the lower face of the upper drum gear 12. In either case; the adjustment is effected 105 with reference to a stationary abutment upon said arbor 8 which precisely determines the position in which the upper drum gear 12 is presented and maintained with respect to said gear 32 which meshes with 110 it. It is convenient to form said abutment by a sheet metal collar pressed on said arbor 8 as above described, merely because of the low cost of such construction, and it is to be understood that a suitable abutment may 115 be formed by a shoulder on said arbor in unitary relation therewith; of course, necessitating the use of a larger diameter of metal than is required by the construction shown. Or said abutment may be formed 120 by a collar which is adjustable axially on said arbor and secured in adjusted position by a set screw.

Although I find it convenient to make said gears 12 and 32 of substantially flat 125 sheet metal stampings, because they may be thus made at less cost than otherwise; of course, they may be respectively beveled for coöperative engagement in the ordinary manner. In either case, the method of ad- 130

justably assembling them in proper relation, above described, may be advantageously employed.

Said winding shaft 31 is adapted to be 5 manually turned in the direction of the arrow marked thereon in Fig. I to wind by means of a crank handle 78 which is, conveniently, detachably connected therewith by the screw thread 79. As reverse rotation 10 of said shaft 31 might disengage the inner ends of said springs from their connections with the arbor 8; I prefer to provide a clutch, supported by said frame flange 3, permitting said winding shaft to turn in 15 the proper direction, but preventing it from turning in the opposite direction. As best shown in Fig. IX, said clutch includes the coil 80 of spring wire in said tubular bearing 30, in frictional engagement with said 20 shaft 31, with its outer end free, but having its inner end extending tangentially through the opening 81 in said bearing 30 and forming the bight 82 exterior to said bearing. Said inner end of said clutch coil is held 25 stationary by means exterior to said bearing 30, conveniently including the screw 83 extending through said bight in engagement with said flange 3.

Said friction clutch is claimed in my 30 pending application for Letters Patent of the United States which is Serial Number 115,504.

I do not desire to limit myself to the precise details of construction and arrangement 35 herein set forth, as it is obvious that various modifications may be made therein without departing from the essential features of my invention as defined in the appended claims.

I claim:—

40 1. In a spring motor, a frame including two plane sheet metal plates, in parallel spaced relation, one having a flange bent toward the other, at right angles to its plane, and cylindrical standards, each riveted in 45 one of said plates and having screw means detachably rigidly connecting it with the other of said plates; a spring arbor journaled in said plates, parallel with and between said standards; a spring drum loose on said arbor and having a gear; a spring in 50 said drum having one end connected to said drum and the other end connected to said arbor; a second spring drum loose on said arbor and having a gear; a spring in 55 said second drum having one end connected to said drum and the other end connected to said arbor; a bearing tube rigidly mounted in said flange in radial relation to said arbor; a winding shaft journaled in said 60 bearing tube and having a gear engaging said first drum gear; a main shaft parallel with said arbor; a counter shaft parallel with said arbor; a worm shaft parallel with said winding shaft; and a train of gears connecting said 65 second drum gear with said counter shaft, main shaft, and worm shaft; and a governor mechanism operatively connected with said worm shaft.

necting said second drum gear with said 65 counter shaft, main shaft, and worm shaft; and a governor mechanism operatively connected with said worm shaft.

2. In a spring motor, a frame including two metal plates, in parallel spaced relation, 70 one having a flange extending toward the other, at right angles to its plane, and standards, detachably rigidly connecting said plates; a spring arbor journaled in said plates; a spring drum loose on said arbor 75 and having a gear; a spring in said drum having one end connected to said drum and the other end connected to said arbor; a second spring drum loose on said arbor and having a gear; a spring in said second drum 80 having one end connected to said drum and the other end connected to said arbor; a bearing tube rigidly mounted in said flange in radial relation to said arbor; a winding shaft journaled in said bearing tube and 85 having a gear engaging said first drum gear; a main shaft parallel with said arbor; a counter shaft parallel with said arbor; a worm shaft parallel with said winding shaft; and a train of gears connecting said 90 second drum gear with said counter shaft, main shaft, and worm shaft; and a governor mechanism operatively connected with said worm shaft.

3. In a spring motor, a frame including 95 two plane sheet metal plates, in parallel spaced relation, one having a flange bent toward the other, at right angles to its plane, and standards, detachably rigidly connecting said plates; a spring arbor journaled in 100 said plates, parallel with and between said standards; a spring drum loose on said arbor and having a gear; a spring in said drum having one end connected to said drum and the other end connected to said arbor; a bearing tube rigidly mounted in said flange in radial relation to said arbor; a winding shaft journaled in said bearing tube and 105 having a gear engaging said drum gear; a main shaft parallel with said arbor; a 110 counter shaft parallel with said arbor; a worm shaft parallel with said winding shaft; and a train of gears connecting said second drum gear with said counter shaft, main shaft, and worm shaft; and a governor 115 mechanism operatively connected with said worm shaft.

4. In a spring motor, a frame including two metal plates, in spaced relation, one having a flange extending toward the other, and 120 means detachably rigidly connecting said plates; a spring arbor journaled in said plates; a spring drum on said arbor, having a gear; a bearing tube rigidly mounted in said flange in radial relation to said arbor; a winding shaft journaled in said bearing tube and having a gear engaging said 125 drum gear; and a clutch in said tube permit-

ting said winding shaft to turn in the proper direction, but preventing it from turning in the opposite direction.

5. In a spring motor, the combination with an arbor, having a fixed abutment, extending transversely to its axis; of two drums having bearings fitted to turn on said arbor, upon the same side of said abutment; and two springs, respectively mounted 10 ed in said drums, each having its outer end detachably connected with its drum, and its inner end detachably connected with said arbor; the spring attaching means on said arbor being studs which are respectively detachable therefrom to permit the passage 15 of said bearings to and from the end of said arbor remote from said abutment.

6. In a spring motor, the combination with an arbor, having a fixed abutment, extending transversely to its axis; of two drums having bearings fitted to turn on said arbor, upon the same side of said abutment; and two springs, respectively mounted in 20 said drums, each having its outer end detachably connected with its drum, and its inner end detachably connected with said arbor.

7. In a spring motor, a frame including a sheet metal plate having a flange bent at 30 right angles to its plane; a bearing in said flange for one end of a shaft; a reinforcing plate; and a stud riveted through said two plates, at one end, and having a shaft bearing at its other end, in alinement with said bearing in said flange.

8. In a spring motor, a frame including a sheet metal plate having a flange bent at right angles to its plane; a bearing in said flange for one end of a shaft; and a stud 40 riveted through said plate, at one end, and having a shaft bearing at its other end, in alinement with said bearing in said flange.

9. In a spring motor, the combination with a frame including three parallel plates, 45 the intermediate plate being in contact with one of the outer plates and in spaced relation with the other plate; of means rigidly connecting said contiguous plates, including a stud having a shaft bearing; means detachably rigidly connecting said outer 50 plates, independently of said intermediate plates, a spring arbor journaled in said plate; a spring arbor journaled in said

outer plates, independently of said intermediate plate; a main shaft journaled in all three plates; means operatively connecting 55 said arbor and main shaft; a governor shaft journaled in said stud bearing; and means operatively connecting said main shaft with said governor shaft.

10. In a spring motor, the combination with a frame including three parallel plates, the intermediate plate being in contact with one of the outer plates and in spaced relation with the other plate; of means rigidly connecting said contiguous plates; means 60 detachably rigidly connecting said outer plates, independently of said intermediate plate; a spring arbor journaled in said outer plates, independently of said intermediate plate; a main shaft journaled in all three 65 plates; means operatively connecting said arbor and main shaft; a governor shaft; and means operatively connecting said main shaft with said governor shaft.

11. In a spring motor, the combination with three parallel frame plates, the intermediate plate being in contact with one of the outer plates and in spaced relation with the other plate; of means rigidly connecting 75 said contiguous plates, including a stud, independent of said other outer plate and having an adjustable shaft bearing at its free end; of a shaft journaled in said stud bearing; a spring arbor journaled in two of said frames; and means operatively connecting 80 said shaft and arbor.

12. In a spring motor, the combination with three parallel frame plates, the intermediate plate being in contact with one of the outer plates and in spaced relation with the other plate; of means rigidly connecting 85 said contiguous plates, including a stud, independent of said other outer plate and having a shaft bearing; of a shaft journaled in said stud bearing; a spring arbor 90 journaled in two of said frames; and means operatively connecting said shaft and arbor.

In testimony whereof, I have hereunto signed my name at Philadelphia, Pennsylvania, this twenty-second day of June, 1916.

THEO CLIFFORD WHITING.

Witnesses:

ARTHUR E. PAIGE,
ANNA ISRAELVITZ.
